UNITED STATES PATENT OFFICE

1,969,973

MARKER FOR SHOE UPPERS

Charles Elmer Edwards, Manchester, N. H., assignor to Perfection Marker Company, Cambridge, Mass., a corporation of Massachusetts

Application May 27, 1933, Serial No. 673,158

12 Claims. (Cl. 101—28)

This invention relates to markers for sheet material and more particularly to marking plates of the type used in applying ornamental patterns, designs, and the like to such articles as vamps, quarters and shoe upper sections generally.

In order properly to position the upper on the marking plate it is customary to provide positioning members which are so designed as not to interfere with the proper operation of the beam or head of the press in which the operation is usually carried out. Marking plates answering this purpose are commonly provided with "disappearing" pins or stops such, for example, as are shown in the United States patents to Woodworth No. 1,733,638 and Lupien No. 1,689,633. Such marking plates are not only relatively expensive to construct, but their use is limited to the one particular style and pattern. The constantly changing styles, particularly in women's shoes, require new or different ornamental designs or patterns and consequently the marking plates become obsolete after a relatively short period of use. The cost of replacing obsolete plates and the number of replacements necessary in the course of a year amount to an appreciable sum and constitute a substantial part of the manufacturing cost of such footwear.

The principal object of the present invention is to provide a marking plate of the aforesaid character which is of simple construction and reliable and accurate in operation, which may be readily constructed of inexpensive materials at a small fraction of the cost of the marking plates now used, and which possesses all of the advantageous features of the various types heretofore used.

Further objects relate to the construction of my new marking plate and will be apparent to those skilled in the art from a consideration of the following description and accompanying drawing which shows one embodiment of the invention chosen for the purpose of illustration.

In the drawing:

Fig. 1 is a plan view of a marking plate constructed in accordance with the present invention, showing a shoe quarter disposed in proper registry on its face;

Fig. 2 is an enlarged section on the line 2—2 of Fig. 1;

Fig. 3 is a diagrammatic elevation showing the marking plate and shoe quarter inserted in a press, the beam or head being shown in raised position;

Fig. 4 is a sectional detail of the parts shown

in Fig. 3, the head of the press being shown in contact with the quarter to be marked; and

Figs. 5 and 6 are enlarged fragmentary sectional views of positioning members embodying a modified construction.

The embodiment chosen for illustration comprises a marking plate 10 which may be of thin metal, such, for example, as galvanized iron, sheet steel, or other suitable material capable of being embossed or otherwise provided with markings which define the desired pattern, design, or ornamentation to be applied to a piece of sheet material, such as a shoe upper section or quarter V. As here shown, the marking plate consists of a single piece of sheet metal provided with rows of small bosses or projections 11, struck up from the under side of the plate 10, although, if desired, perforating dies or any other type of marking means may be used, it being understood that the particular type of marking means on the plate 10, as well as the design or pattern, may be varied to produce whatever ornamental effect is desired.

In order properly to position the material or quarter on the marking plate, positioning members are provided at a plurality of fixed points spaced from the markings 11. In accordance with the present invention, these members are sufficiently resilient and are so constructed and arranged that they may be depressed by being crushed or flattened down under pressure so that their abutting surfaces either lie substantially in the plane of the material, or do not project to any appreciable extent above the same when subjected to pressures such as are used to impress or apply the markings to the material to be marked.

In this particular embodiment, the plate 10 is provided with circular openings 14 spaced predetermined distances from the markings 11, there preferably being three such openings in order to insure the correct positioning of the material relative to the markings 11. The positioning members 12 are preferably of sponge rubber in the form of cylindrical pegs, although I contemplate the use of any other high compressible material having sufficient elasticity to recover substantially its original shape after being collapsed or deformed. The pegs 12 are of a greater cross-sectional area than the openings 14, and are wedged within the openings, as shown in Fig. 2, so as to be anchored firmly in fixed position. Due to the contraction of the central portion of the pegs, they assume a frusto-conical shape which provides overhanging portions or lips 15 which over-

lie the margins of the quarter V and are effective to hold the same in fixed position on the marking plate 10.

The marking plate 10 may, if desired, be superposed on a supporting plate 16 of fiber board or the like material, which may be provided with suitable openings or recesses 17 for the reception of the downwardly projecting ends of the pegs 12, and the assemblage may be secured in any suitable manner to a base plate 18 which may be of any desired size or shape so as to be conveniently inserted in a press.

In using a marker constructed in accordance with the present invention, the material or quarter V to be marked is placed on the exposed surface of the marking plate, grain side down, with its edges in contact with each of the members 12, as shown in Figs. 1 and 2. The marking plate and positioned quarter are then laid on the work bed of a suitable press P, as shown in Fig. 3, and the head or beam 19, the under side of which is preferably lined with a resilient pad 20, such as rubber or felt, is then brought downwardly upon the quarter with sufficient force or pressure to effect the desired impression or transfer of the design.

As shown in Fig. 4, the pegs 12 are collapsed and depressed so that their projecting portions and overhanging lips 15 lie substantially in the plane of the quarter V, and thus do not interfere with the proper operation of the head 19 of the press. When the head is released, the pegs 12 immediately recover their normal shape and position, and the marked quarter may then be stripped from the plate 10.

The use of sponge rubber pegs is particularly advantageous as this material is not only relatively inexpensive, but pegs of any desired size and shape may be easily cut from a blank sheet of stock. Furthermore, this material possesses the property of being able to grip and hold on to the edge and marginal portions of the sheet material, and thus may be depended upon to hold the material in proper position on the marking plate. I have also found that sponge rubber pegs may be subjected to considerable pressure and distorted an indefinite number of times before a measurable permanent set or distortion takes place, and that such pegs will, in most cases, out-wear the markings on the marking plate.

The positioning members shown in Figs. 5 and 6 have the same general construction and function as that shown in the previously described embodiment. The member 30 shown in Fig. 5 comprises an upstanding portion 31 which is provided with an integral lip 32 arranged to overlie the margin of the quarter V to hold the same in fixed position relative to the marking plate 10. The member 30 is of highly compressible material, such as soft or sponge rubber, and is secured in fixed position on the marking plate 10 by suitable adhesive, such as a layer 33 of rubber cement.

The member 34 shown in Fig. 6 is similar in shape to the member 30, but is of laminated construction, comprising outer layers 35 and 36, each of which is preferably of a relatively firm material, although somewhat resilient and compressible, such as for example, as ordinary sheet rubber. The intermediate layer 37 is of highly compressible material, such as soft or sponge rubber, and has a thickness which is preferably at least as great as the combined thickness of the outer layers 35 and 36 to permit the entire member to be depressed or flattened sufficiently so that the upper layer 35 will not project appreciably above

the upper surface of the quarter V when subjected to pressure in the manner previously explained. The upper layer 35 extends laterally beyond the upright edges of the intermediate and base layers 37 and 36, respectively, to provide an overhanging lip 38 engageable with the margins of the quarter V. The entire member may be firmly secured in fixed position to the marking plate 10 by means of a layer 39 of suitable adhesive, as in the previously described embodiment.

It will be noted that in a marker embodying the construction shown in Fig. 5 or Fig. 6, the use of an intermediate supporting plate and a base plate is dispensed with, and that as the total thickness of the marker is greatly reduced, it is possible to insert a greater number of markers in a press at one time.

The terms "marker" and "markings" as herein used, unless otherwise limited expressly or by context, are intended to denote any of the instruments and operations for applying markings, designs or patterns to sheet material, including markings by printing from a transfer sheet which is commonly used as a guide for subsequent stitching, markings by indentation of the surface of the sheet simulating stitching or producing other ornamental effects, perforating the sheet by punching holes completely through it, forming imitation perforations which simulate true perforations but are in reality non-perforating indentations, and embossings generally.

While I have shown and described one desirable embodiment of the present invention, it is to be understood that this disclosure is for the purpose of illustration only, and that various changes in shape, proportion and arrangement of parts, as well as the substitution of equivalent elements for those herein shown and described, may be made without departing from the spirit and scope of the invention as set forth in the appended claims.

I claim:

1. A marker for use in applying a design or the like to a piece of sheet material, said marker comprising a plate having on its surface markings defining the design to be applied to the sheet material, and means for positioning the sheet material relative to the markings on said plate, said means comprising upwardly projecting members disposed in fixed position relative to the markings on said plate, the projecting portions of said members being of an inherently resilient and highly compressible organic material capable of being depressed so as to lie substantially in the plane of the sheet material when pressure is applied thereto.

2. A marker for use in applying a design or the like to a piece of sheet material, said marker comprising a plate having on its surface markings defining the design to be applied to the sheet material, and means for positioning the sheet material relative to the markings on said plate, said means comprising upwardly projecting members having overhanging portions adapted to engage the margins of the sheet material and hold the same in fixed position relative to the markings on said plate, said members being of an inherently resilient and highly compressible organic material capable of being depressed so that said overhanging portions lie substantially in the plane of the surface of said sheet material when subjected to pressure.

3. A marker for use in applying a design or the like to a piece of sheet material, said marker comprising a plate having on its surface mark-

- ings defining the design to be applied to the sheet material, and means for positioning the sheet material relative to the markings on said plate, said means comprising a plurality of gauge members secured to said plate in spaced relation to the markings thereon, each of said members being of an inherently resilient and highly compressible organic material capable of being depressed so as to lie substantially in the plane of the sheet material when subjected to pressure. 5
4. A marker for use in applying a design or the like to a piece of sheet material, said marker comprising a plate having on its surface markings defining the design to be applied to the sheet material, and means for positioning the sheet material relative to the markings on said plate, said means comprising a plurality of gauge members secured to said plate in spaced relation to the markings thereon, said members being of a soft inherently compressible rubber-like material having sufficient resiliency to be depressed below the surface of said sheet material when subjected to pressure. 10
5. A marker for use in applying a design or the like to a piece of sheet material, said marker comprising a plate having on its surface markings defining the design to be applied to the sheet material, and means for positioning the sheet material relative to the markings on said plate, said means consisting of soft rubber members secured to said plate in spaced relation to the markings thereon. 15
6. A marker for use in applying a design or the like to a piece of sheet material, said marker comprising a plate having on its surface markings defining the design to be applied to the sheet material, and means for positioning the sheet material relative to the markings on said plate, said means consisting of sponge rubber pegs secured to said plate in spaced relation to the markings thereon. 20
7. A marker for use in applying a design or the like to a piece of sheet material, said marker comprising a plate having on its surface markings defining the design to be applied to the sheet material, and means for positioning the sheet material relative to the markings on said plate, said means consisting of sponge rubber pegs secured to said plate in spaced relation to the markings thereon, said pegs being of frusto-conical shape to provide overhanging portions engageable with the margins of the sheet material to hold the same in fixed position relative to the markings on said plate. 25
8. A marker for use in applying a design or the like to a piece of sheet material, said marker comprising a plate having on its surface markings defining the design to be applied to the sheet material, said plate having openings therein spaced from the markings thereon, and means for positioning the sheet material relative to said markings, said means consisting of soft rubber pegs wedged in the opening in said plate. 30
9. A marker for use in applying a design or the like to a piece of sheet material, said marker comprising a plate having on its surface markings defining the design to be applied to the sheet material, said plate having openings therein spaced from the markings thereon, and means for positioning the sheet material relative to said markings, said means consisting of sponge rubber pegs wedged in said openings so as to present portions which overhang the margins of said sheet material and hold the same in fixed position relative to the markings on said plate. 35
10. A marker for use in applying a design or the like to a piece of sheet material, said marker comprising a plate having on its surface marking defining the design to be applied to the sheet material, and means for positioning the sheet material in fixed position relative to the markings on said plate, said means comprising a plurality of guide members adhesively secured to said plate in spaced relation to the markings thereon, each of said members having an overhanging lip engageable with the margin of the sheet material, said members including portions consisting of an inherently resilient and highly compressible organic material capable of being depressed so that the lips lie substantially in the plane of the sheet material when subjected to pressure. 40
11. A marker for use in applying a design or the like to a piece of sheet material, said marker comprising a plate having on its surface marking defining the design to be applied to the sheet material, and means for positioning the sheet material in fixed position relative to the markings on said plate, said means comprising a plurality of guide members secured to said plate in spaced relation to the markings thereon, each of said members being shaped to provide an integral overhanging lip engageable with the margin of the sheet material, said members being composed of soft rubber capable of being depressed so that the lips lie substantially in the plane of the sheet material when subjected to pressure. 45
12. A marker for use in applying a design or the like to a piece of sheet material, said marker comprising a plate having on its surface marking defining the design to be applied to the sheet material, and means for positioning the sheet material in fixed position relative to the markings on said plate, said means comprising a plurality of guide members secured to said plate in spaced relation to the markings thereon, each of said members having a laminated structure including a layer of highly compressible and resilient organic material, and an upper layer of relatively firm material having a projecting portion providing an overhanging lip engageable with the margin of a positioned piece of sheet material. 50

CHARLES ELMER EDWARDS.
